US00D844630S

(12) **United States Design Patent** (10) Patent No.: **US D844,630 S**
(45) Date of Patent: ** Apr. 2, 2019

(54) **DISC CARTRIDGE**

(71) Applicant: **Sony Corporation**, Tokyo (JP)

(72) Inventors: **Jun Sawai**, Kanagawa (JP); **Jo Wada**, Tokyo (JP); **Takaji Nakamura**, Kanagawa (JP); **Osamu Miki**, Kanagawa (JP)

(73) Assignee: **SONY CORPORATION**, Tokyo (JP)

(**) Term: **15 Years**

(21) Appl. No.: **29/575,936**

(22) Filed: **Aug. 30, 2016**

Related U.S. Application Data

(63) Continuation of application No. 29/421,840, filed on Oct. 3, 2012, now Pat. No. Des. 766,251.

CLAIM

The ornamental design for a disc cartridge, as shown and described.

DESCRIPTION

FIG. 1 is a front, top, right perspective view of a disc cartridge showing our new design;

FIG. 2 is a rear, bottom left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrating the unclaimed portions of the disc cartridge form no part of the claimed design.

1 Claim, 6 Drawing Sheets
